US00D769442S

(12) **United States Design Patent** (10) **Patent No.:** **US D769,442 S**
Nasir et al. (45) **Date of Patent:** **** Oct. 18, 2016**

(54) **AIRWAY DEVICE**

(71) Applicants: **Muhammed Aslam Nasir**,
 Bedfordshire (GB); **Surinderjit Jassell**,
 Berkshire (GB)

(72) Inventors: **Muhammed Aslam Nasir**,
 Bedfordshire (GB); **Surinderjit Jassell**,
 Berkshire (GB)

(73) Assignee: **ASHKAL DEVELOPMENTS
 LIMITED (IM)**

(**) Term: **14 Years**

(21) Appl. No.: **29/512,932**

(22) Filed: **Dec. 23, 2014**

Related U.S. Application Data

(62) Division of application No. 29/428,284, filed on Jul. 27, 2012.

Foreign Application Priority Data

Jan. 27, 2012 (EM) 001982620
 Jan. 27, 2012 (EM) 002079210

(74) *Attorney, Agent, or Firm* — Hayes Soloway P.C.

(57) CLAIM

The ornamental design for an airway device, as shown and described.

DESCRIPTION

FIG. 1 is a top view of an airway device, showing our new design;

FIG. 2 is a bottom side view thereof;

FIG. 3 is a right side view thereof;

FIG. 4 is a left side view thereof;

FIG. 5 is a rear view thereof;

FIG. 6 is a front view thereof;

FIG. 7 is a top perspective view thereof; and,

FIG. 8 is a bottom perspective view thereof.

The broken lines in the drawings illustrate portions of the airway device which form no part of the claimed design.

1 Claim, 4 Drawing Sheets
